UNITED STATES PATENT OFFICE.

ANDREW SNOW, JR., OF NEW BEDFORD, MASSACHUSETTS.

DESIGN FOR A GLASS RECEPTACLE.

SPECIFICATION forming part of Design No. 28,178, dated January 18, 1898.

Application filed November 3, 1897. Serial No. 657,297. Term of patent 34 years.

To all whom it may concern:

Be it known that I, ANDREW SNOW, Jr., of New Bedford, in the county of Bristol and State of Massachusetts, have invented a new and original Design for a Glass Receptacle, of which the following is a specification, reference being had to the accompanying drawings, in which—

Figure 1 represents a plan view, and Fig. 10 2 a sectional elevation on line 2 2 of Fig. 1.

The leading feature of my design consists of a many-pointed star in the middle of the base of the dish, surrounded by a circle of upwardly-extending rays. Another feature of 15 my design consists in a marginal row of round plain-surfaced depressions on the outer sides of the dish and adjacent to its edge, which is divided into lobes.

A is the many-pointed star, and is in the 20 center of the base, and consists of a central rosette a , surrounded by short straight intersecting lines forming a circle of small pyramids a' , surrounding the rosette a . The points a^2 of the star are formed by intersecting indentations, and each point a^2 is subdivided by three short straight indentations.

B is the circle of rays entirely surrounding the star A and is made up of the short rays b and the long rays b' , so arranged that the 25 long rays are separated from each other by

two short rays. These rays are deep indentations cut into the glass. The spaces b^2 between the rays are cut in such a manner by alternate broad and narrow transverse cuts as to give the circle of rays the appearance of 35 being cut by a number of concentric circles. Outside of this band of rays is a marginal band of slightly-concaved and smooth-surfaced depressions C, each circular in form and so arranged that one circle falls between 40 every two of the long rays b' . The edge of the dish is divided into broad lobes D, which are subdivided into smaller lobes d . Between the broad lobes D are small points d' . The lobes D are of such length and form as 45 to have each lobe cover one of the concaved circles C.

What I claim, and desire to secure by Letters Patent, is—

The design for a glass receptacle as herein 50 shown and described.

In testimony whereof I have signed my name to this specification, in the presence of two subscribing witnesses, on this 23d day of August, A. D. 1897.

ANDREW SNOW, JR.
